UNITED STATES PATENT OFFICE

WILLIAM JOSEPH BOESCH, OF PEORIA, ILLINOIS, ASSIGNOR TO THE MEYER FURNACE CO., OF PEORIA, ILLINOIS, A CORPORATION OF ILLINOIS

FURNACE

Application filed March 24, 1928. Serial No. 264,459.

This invention pertains to improvements in heating apparatus. More particularly the invention pertains to the novel construction of a furnace of the hot air type, to a fire pot therefor, and to the sectional construction 5 of the latter.

An object is to provide a fire pot construction in which the walls thereof are spaced from the walls of the furnace body, and to 10 supply air entirely from outside the furnace to pass through the space thus provided for delivery upon the top of the fire, in a well known way, said space being cut off entirely from the fire space and grate and the space 15 below the latter to the end that the air thus inducted cannot affect the draft on the fire.

Another object is to provide an annular hollow ring enclosing the lower part of the fire space and the grate, entirely closed off 20 from both and from the ash-pit, but open outside the furnace, and to mount thereon a fire pot having its fire-space walls spaced from the body of the furnace creating a space to communicate with the space of said 25 ring, said wall of the fire-pot being perforated in a well known way and for a well known purpose, all of the air admitted being inducted from outside the furnace rather than through the grate and fire.

30 Another object is to provide a fire-pot of sections of novel form and the relation thereof to other parts of the furnace structure.

In the appended drawings forming part 35 hereof,

Figure 1 is a sectional elevation of part of a furnace constructed in accordance with the invention.

Figure 2 is a horizontal section of the same on line 2—2, Figure 1.

40 Figure 3 is a front elevation of part of the furnace of my invention showing the furnace body in section.

Figure 4 shows in perspective a section of the fire-pot and an air ring upon which it is 45 mounted, and

Figure 5 is a transverse section of part of a fire-pot section and a part shown in Figure 4.

The construction shown, and herein to be 50 described, includes what I shall term the "furnace body" denoted at 1. This is a well

known steel drum riveted and welded and thoroughly gas tight. Supported therein on suitable brackets 2, for example, is a grate which comprises a ring portion 3 resting on said brackets and snugly fitting the said body

1. It includes suitable grate bars 4, Figures 1 and 2, and the inner edge has an upstanding flange 5. Resting upon the ring portion and abutting against the outside surface of said flange 5 is a ring comprising a vertical wall 6 forming an enclosure for the fuel resting upon the grate, and a wall 7 paralleling the ring portion 3 and abutting against the furnace body 1, an air space 8 being created in this manner which extends entirely around the fire space created by the wall 6. At a 55 convenient point, in this instance in the front of the structure, is an opening 9 for entrance of air through a throat 10 leading from outside any usual outer enclosing casing 11, 60 Figures 1 and 2.

Mounted upon the wall 7 is a series of fire-pot sections denoted in general by 12, 13 and 14. The sections 12, one of which is illustrated separately in Figure 4, each includes a curved inner wall 15 which together with the wall 6 described, form the fire space, these 65 said walls being in alignment in this instance. Said wall 15 at its top curves back toward and abuts against the body 1, and each section has an end wall 16 to abut against neighboring sections, Figure 2, there being intermediate strengthening walls 17, Figure 4, all the walls mentioned abutting also upon the body 1.

80 Preferably, the ring 6, 7 has an upstanding flange 6' beneath the wall 15 upon which the latter rests, said wall 15, 16 and 17 being formed to correspond as at 6' preventing likelihood of the sections shifting toward the fire space and keeping them in snug abutment upon the 85 said body 1. The several walls 17 create air cells between them, each cell being supplied with air through an opening 7' in the top wall 7 of said ring 6, 7 which air passes out through perforations 18 of the sections upon 90 the fire.

In order to provide an opening into the fire space for feeding fuel from the opening 9, shorter sections as 14 are provided as best 95 shown in Figure 1. These sections are similar 100

to the described sections 12 and may or may not have intermediate walls 14', Figure 3, but in any event air is received into them from the ring 6, 7, and have perforations 14². The other sections previously referred to and denoted by 13 fill the spaces between sections 12 and 14 and are similarly provided with air outlets 13'.

It is observed that the air admitted to the air space 8 of the combined ring structure 3, 6, 7 is taken wholly from outside the furnace through the throat 10 and that none of the air so admitted is permitted to enter the fire space through the grate or otherwise and the draft on the fire cannot be affected. In other words, any air admitted to the grate must be through the usual draft damper, not shown. Due to my improved structure air carried to and upon the fire through the perforations in the several sections 12, 13, 14 for gas consuming purposes is evenly distributed around the fire-pot from the fact that the openings 7' in the ring 6, 7 are comparatively small and each leads separately to a cell of the sections, each cell supplying its own air through the perforations in the top wall. If the cells were all open into the space 8 naturally the flow of air would be through the cells nearest the inlet 9. But as each separate cell is fed by a small opening, at 7', it is clear that the air distributed will be comparatively even throughout and especially if the said openings 7' are made larger as they recede in position from the said inlet 9. The introduction of air jets to the fire space from the fire pot sections is well known but the distribution of the air through all of the perforations evenly around the fire space is important as providing for the best results in furnace operation.

Although the fire-port may be a single member it is preferably made in sections for convenience in installing and for replacing individual sections as occasion arises.

While each of the sections 12, 13, 14 is described as including terminal walls 16, one at each side, I may use but one of such walls on a section and merely abut the open side of one section against the wall 16 of a next section, the one wall answering as two. However the form shown is preferred as adding strength to the unit of which it is a part and preventing distortion under heat, besides which an expansion joint is created between the abutting walls through which, however, dust or ashes cannot readily pass.

I claim:

1. A furnace including in its construction a body, a ring snugly fitting within the same and having a central opening inward from the body creating a grate-space, a second ring comprising a vertical wall separate from and erected upon the first named ring adjacent and enclosing the grate-space and forming a fire-space, said second ring including an an-

nular wall extending outward therefrom abutting the body and lying above and paralleling the said first named ring in spaced relation thereto, the named two rings and the body together creating an annular cavity encircling the fire space, there being perforations in the said annular wall, and a fire-pot mounted upon the said vertical wall spaced from the body and abutting at its top edge against the said body and perforated, and including a series of spaced walls radiating therefrom abutting the said annular wall, certain of the perforations in the annular wall communicating with the cavities between the said radial walls.

2. A furnace including in its construction a body and an annular hollow ring structure creating an annular enclosure outside the fire-space of said furnace, an upper wall of said structure having a series of apertures perforating it, and a fire-pot surmounting the structure comprising an inner fire-wall spaced from the body, said fire-pot having a series of spaced integral vertical walls abutting upon the body and at their lower ends abutting on the ring structure creating closed vertical passages, said apertures opening into the several passages.

3. A furnace including in its construction a body and an annular hollow ring structure creating an annular enclosure outside the fire-space of said furnace, an upper wall of said structure having a series of apertures perforating it, and a series of abutting fire-pot sections mounted on the structure each comprising an inner fire wall spaced from the body and at its top extending to and abutting upon the latter and perforated, each said section having a series of spaced integral outwardly directed vertical walls abutting upon the body and at their lower ends abutting upon the ring structure creating individual vertical passages between them, and said apertures communicating with the passages.

4. A furnace including in combination a furnace body and a perforated supporting ring therein, a hollow fire-pot section having a front fire-wall spaced from the body and resting upon the ring, and including a series of walls extending from the rear side thereof, said front fire-wall at its upper portion extending outwardly over the several walls in abutment with the body, and said supporting ring creating closed passages between the body and the several walls of the section for air travel from the perforations of the ring through the perforations of the said front fire-wall.

5. A fire-pot section for furnaces consisting of a single casting comprising a cylindrically curved main wall and radial walls extending from its convex side, one terminating each end of said main wall, all said radial walls having free edges lying remote from the main wall and paralleling the

straight line surface thereof, the main wall and the radial walls at one extremity being coextensive, and said main wall at its other extremity overlying the other extremities of the radial walls and terminating flush with their said free edges.

6. A fire-pot section for furnaces consisting of a single casting comprising a cylindrically curved main wall and radial walls 10 extending from its convex side, one terminating each end of said main wall, all said radial walls having free edges lying remote from the main wall and paralleling the straight line surface thereof, the main wall and the radial 15 walls at one extremity being coextensive, and said main wall at its other extremity overlying the other extremities of the radial walls and terminating flush with their said free edges, there being perforations in the overlying wall portion between the positions of 20 the radial walls.

7. In a furnace structure, an enclosing furnace body, a ring supported by and fitting within and against the walls of said body, a second ring having a cylindrical wall resting upon and upstanding from the first said ring and spaced from the body including an annular flange overhanging and spaced above the said first ring and abutting upon the 25 body, the two rings forming a closed annular passage with and adjacent the latter, and a fire-pot resting upon the second ring comprising a main wall abutting upon the upstanding cylindrical wall of the latter and 30 having spaced vertical radial walls integral therewith abutting against the body and abutting the said annular flange, the said main wall extending over and upon the upper portions of the said radial walls and 35 having spaced vertical radial walls integral therewith abutting against the body and abutting the said annular flange, the said main wall extending over and upon the upper portions of the said radial walls and 40 abutting the body, there being an opening in that portion of the main wall that extends over the said radial walls, each said opening lying between the positions of any two of the latter, and there being an opening in the first 45 named ring between each of said radial walls resting thereon.

In testimony whereof I affix my signature.
WILLIAM JOSEPH BOESCH.
